UNITED STATES PATENT OFFICE.

JESSE B. HELLER, OF LAKEWOOD, OHIO, ASSIGNOR TO NATIONAL MOTOR CONTROL CO., A CORPORATION OF DELAWARE.

PERMUTATION LOCK.

1,427,382.

Specification of Letters Patent. Patented Aug. 29, 1922.

Application filed February 28, 1920. Serial No. 362,167.

To all whom it may concern:

Be it known that I, JESSE B. HELLER, a citizen of the United States, residing at Lakewood, in the county of Cuyahoga and 5 State of Ohio, have invented certain new and useful Improvements in Permutation Locks, of which the following is a specification.

Figure 1 is a plan view with parts broken 10 away of one form of lock embodying my invention,

Figure 2 is a side elevation with the cover and shells in section,

Figure 3 is a sectional view on the line 15 111—111 of Fig. 4,

Figure 4 is a sectional view on the line IV—IV of Fig. 3,

Figure 5 is a sectional plan view on the line V—V of Fig. 2, with the parts in their 20 fully locked position,

Figure 6 is a view similar to Fig. 5, from which some of the parts have been omitted for clearness, and in which the lock parts have been shifted one point,

25 Figure 7 is another view similar to Fig. 5, in which the lock parts have been shifted four points, to unlock the switch operating shaft,

Figure 8 is still another view similar to 30 Fig. 5, in which the switch shaft has been shifted,

Figure 9 is a sectional view on the line IX—IX of Fig. 4, with the parts in the position shown in Figs. 1—5,

35 Figure 10 is a sectional view on the line X—X of Fig. 2, with the parts in the position shown in Fig. 8,

Figure 11 is a detail sectional view on the line XI—XI of Fig. 1,

40 Figure 12 is a perspective view of one of the actuating push buttons.

This invention relates to an improvement in permutation locks, and more specifically to locks for electric switches.

45 The lock parts shown are generally similar to those shown in my co-pending application, Serial No. 301,319, filed June 2, 1919, the patent to O. P. Barnes, No. 1,316,934, of September 23, 1919, and the application of 50 R. R. Barnes, Serial No. 361,928, filed Feb. 28, 1920.

The object of my invention is to provide a simple and efficient locking device in connection with permutation locks which will 55 permit the permutation mechanism to be

moved a predetermined distance before the lock is released, together with a lock so arranged that when the lock is moved from its unlocked to its locked position, it will move the permutation mechanism to zero, or what 60 is generally termed its fully locked position.

In this case I have shown the lock in connection with a well known snap switch, and which is thrown from one extreme to the other by a spring actuated toggle, the 65 parts being so arranged to hold the switch in its extreme positions by the action of the spring. The toggle is actuated by an oscillating shaft which is locked against movement when the switch is open, and which 70 lock is released by the permutation mechanism, when said mechanism has been moved a predetermined distance to permit the switch to be closed.

The lock parts are arranged to shift the 75 permutation mechanism to zero or their fully locked position when the switch is opened, and at the same time lock the switch against movement to its closed position.

The precise nature of my invention will 80 be best understood by reference to the accompanying drawings, which will now be described, it being premised, however, that various changes may be made in the details of construction and arrangement of the 85 parts, without departing from the spirit and scope of my invention, as defined in the appended claims.

Referring to the accompanying drawings, the reference character 10 designates a base 90 having an upwardly extending hollow spindle 11. 12 is a combination wheel or lock releasing member mounted on the spindle 11, and which is arranged to be moved four points in one direction by cams 95 13 on push buttons 14, through the medium of four pins 15 in the combination wheel 12.

These pins 15 are placed in a predetermined position on the combination wheel 12 to advance the combination wheel four points 100 step-by-step, from zero to its unlocking position, when the buttons 14, (which I have designated 1—8) are operated in a prearranged order.

The combination wheel 12 is held in its 105 different positions by a spring pawl 16 which engages recesses in the combination wheel 12.

Mounted to oscillate on the combination wheel 12 between the upper face thereof and a flanged collar 17 secured to the combina- 110

tion wheel by screws 18, is a trip wheel 19, for returning the combination wheel step-by-step to zero through the medium of friction clutch members 19^a, when the buttons 5 14, are actuated out of order.

The trip wheel 19 is oscillated by radial projections 20 on the buttons 14, which enter helical grooves in the trip wheel, there being eight such grooves shown, one for 10 each projection 20 on the eight buttons 14. In order to hold the trip wheel 19 in a fixed position with relation to the buttons 14, I provide a spring actuated lever 21 which oscillates on the hollow spindle 11.

15 22 is a spring connected to the lever 21 and a spring holder 23 secured as hereinafter described.

The buttons 14 are normally held in their elevated positions by means of springs 24^a 20 which are seated in recesses in the push buttons 14 and which engage the base 10.

The buttons 14 are adapted to reciprocate in guides in a shell 24, which is secured to a shell 25 by screws 26, the base 10 being 25 clamped in position between the shells.

The spring holder 23 is clamped in position on one of the lugs for the securing screws 26 on the shell 24 by the screw passing through said lug.

30 27 is a cover for the shell 24 which is locked in position by a spring bolt 28, see Figure 11.

Mounted within the shell 25 is a snap switch having a switch blade 29 which is arranged to close the circuit across spring contacts 30 and 31 secured to a block or base 32 of insulating material secured to the bottom of the shell 25.

The switch blade 29 is connected to a toggle lever 33 pivoted on a frame 34 connected to the block 32, and which toggle lever 33 is actuated by a compression spring 35 on a connecting rod connected to a crank 36. The crank 36 is pivoted in the frame 34 and is connected to a shaft 37 mounted in the hollow spindle 11, and which shaft extends from the shell 25 to the outside of the cover 27.

Secured to the squared upper end of the 50 shaft 37 by means of a screw is a turn button 38 for actuating the switch.

The lower end of the shaft 37 is also squared, and connected thereto by a screw, is a lever 39 which extends into the shell 24 55 through an opening through a hollow boss on the lower end of the hollow spindle 11. The lower end of the hub of lever 39 is slotted to receive a flat portion on the crank 36, there being insulating material between the 60 crank and the hub of lever 39, to prevent grounding of the circuit controlled by the switch.

Pivotedly connected to the outer end of lever 39 is a latch or lock lever 40, which is 65 normally held in its working position by a

leaf spring connected to the latch lever, and which bears against the hollow boss on the lower end of spindle 11.

One end of the latch lever 40 is recessed to engage a projection 41 on the base 10, to 70 lock the switch in its open position, while the other end of the latch lever is arranged to be engaged by a cam 42 on the combination wheel 12 to free the latch lever from the projection 41 when the combination 75 wheel has been advanced four points from zero. The last mentioned end of latch lever 40 is also arranged to engage a tooth 43 on the combination wheel 12 to return the permutation mechanism to zero when the switch 80 is opened.

The permutation mechanism in Figures 1 to 5 is at zero, and the switch in said figures as well as Figure 9 is in its open position. When it is desired to close the switch the 85 permutation mechanism must be moved four steps to bring the mechanism from the position shown in Figure 5 to that shown in Figure 7, which is accomplished in this lock by pushing buttons 7—5, 3—4 in sequence. 90 When buttons 7, 5, 3 are pushed the permutation mechanism will be shifted from the position shown in Figure 5 to that shown in Figure 6, and when button 4 is pushed, the permutation mechanism will be shifted to 95 the position shown in Figure 7. The action of cam 42 on the latch lever 40 will release the latch lever from projection 41 and permit the shaft 37 to be rotated by means of the turn-button approximately 90°, from the 100 position shown in Figures 5, 6 and 7 to that shown in Figure 8. This shifting of the shaft will throw the switch from the position shown in Figure 9 to that shown in Figure 10. When the switch is thrown in the 105 reverse direction to open the circuit, the shaft 37 is rotated clockwise from the position shown in Figure 8 to that shown in Figures 5, 6 and 7, and during the clockwise 110 movement of this shaft the end of the latch 110 lever 40 will engage the tooth 43, and shift the permutation mechanism to zero. Just before the permutation mechanism is shifted to zero, the end of the latch lever 40 will engage the projection 41, which will release the front end of the latch lever from the tooth 43, and permit the latch lever to pass beyond said tooth a sufficient distance to permit the notched end of the latch lever to engage the projection 41 to lock the switch 120 against movement, as clearly shown in Figure 5.

If the 7 and 5 buttons are pushed in sequence, and any of the other buttons with the exception of button 3 are then pushed, 125 the permutation mechanism will be returned to zero by the trip wheel 19, through the medium of the spring-pressed friction clutch members 19^a which is arranged to actuate the combination wheels 12 counter 130

clockwise, but will permit the trip wheel 19 to move freely in a clockwise direction.

The advantages of my invention result 5 from the provision of the lock for a switch actuating shaft or similar member, which is arranged to be released by permutation mechanism when the permutation mechanism is moved a predetermined distance, and which permutation mechanism is adapted to 10 be oscillated within a pre-arranged limit without affecting the locking mechanism. Another advantage of my invention results 15 from the provision of locking mechanism which is arranged to return the permutation mechanism to zero when the locking mechanism is shifted from its unlocked position to its locked position.

I claim:-

1. A permutation lock, comprising a 20 spindle, a combination wheel on the spindle, a return wheel, means for moving the combination wheel step-by-step from zero when operated in a prearranged order and for operating the trip wheel, actuating connections between the trip wheel and combination wheel, a latch device for the spindle, and means actuated by the combination wheel when moved a predetermined distance from zero to release said latch, substantially as described.

2. A permutation lock, comprising a spindle, a combination wheel on the spindle, a return wheel, means for moving the combination wheel step-by-step from zero when 35 operated in a pre-arranged order and for operating the trip wheel, actuating connections between the trip wheel and combination wheel, a latch device for the spindle, means actuated by the combination 40 wheel when moved a predetermined distance from zero to release said latch, and means for returning the permutation mechanism by the latching means when the locking means is moved from its unlatched to its 45 latched position, substantially as described.

3. A permutation lock, comprising a combination wheel, a return wheel, a friction clutch between the combination wheel and the return wheel, means for moving the com-

bination wheel step-by-step from zero when 50 operated in a pre-arranged order and for operating the trip wheel, a latch device, and means actuated by the combination wheel when moved a predetermined distance from zero to release said latch, substantially as 55 described.

4. A permutation lock, comprising a combination wheel, a return wheel, a friction clutch between the combination wheel and the return wheel, means for moving the combination wheel step-by-step from zero when 60 operated in a pre-arranged order and for operating the trip wheel, a latch device, means actuated by the combination wheel when moved a predetermined distance from 65 zero to release said latch, and means for returning the permutation mechanism by the locking means when the locking means is moved from its unlocked to its locked position, substantially as described.

5. An electrical switch lock comprising 70 permutation mechanism including a combination wheel, push buttons for actuating the combination wheel, a return wheel, actuating mechanism between the return 75 wheel and the combination wheel, a latch member for the electrical switch for latching it in its open position, and means on the combination wheel for releasing the latch when moved a predetermined distance, substantially as described.

6. An electrical switch lock comprising 80 permutation mechanism including a combination wheel, push buttons for actuating the combination wheel, a return wheel, 55 actuating mechanism between the return wheel and the combination wheel, a latch member for the electrical switch for latching it in its open position, means on the combination wheel for releasing the latch 60 when moved a predetermined distance, and means on the latching means for returning the lock parts to their initial positions when the switch is thrown from its closed to its open position, substantially as described.

In testimony whereof, I affix my signature.

JESSE B. HELLER.
